UNITED STATES PATENT OFFICE

ISIDORE SIMON, OF CHICAGO, ILLINOIS

HEEL

Application filed November 28, 1928. Serial No. 322,396.

My invention relates broadly to molded articles and has to do more particularly with shoe heels made of molded or plastic material, such as a phenol condensation product, 5 hard rubber or the like. The invention has among its objects the production of a device of the kind described which is attractive, of light weight, simple in construction, durable, and satisfactory for use wherever found applicable.

More broadly, it has as an object the production of a heel formed of a material that may be readily molded or shaped, which will be hard and durable, impervious to moisture, having a high polish, and which will have any desired color to match various kinds of leather or other material from which shoes are formed, and which may be readily attached to a shoe, and when so attached will 20 be firmly held in place.

Many other objects and advantages of the construction herein shown and described will be obvious to those skilled in the art from the disclosure herein given.

To this end my invention consists in the novel construction, arrangement and combination of parts herein shown and described, and more particularly pointed out in the claims.

Referring now to the drawings forming part of this specification which illustrate certain preferred embodiments of my invention:

Fig. 1 represents a top plan view of a heel embodying one form of my invention;

Fig. 2 is a sectional view taken on the line 2—2 of Fig. 1;

Fig. 3 is a sectional view similar to Fig. 2 but representing another embodiment of my invention;

Fig. 4 is a similar sectional view representing still another embodiment.

Fig. 5 is a perspective view of a metallic insert used in the embodiment of Figs. 1 and 2;

Fig. 6 is a perspective view of an insert as used in the embodiment of Fig. 3;

Fig. 7 is a perspective view of another insert used in the device of Figs. 1 and 2; and

Fig. 8 is a fragmentary detail section showing still another embodiment.

Referring first to the embodiment shown in Figs. 1 and 2, the numeral 10 indicates a shoe heel formed preferably of plastic material such as a phenol condensation product, vulcanized rubber, or other suitable plastic material.

As shown best in Fig. 2, the heel is formed with a concavity 12 in its upper portion and with a central opening 13, so that the plastic body 10 is substantially tubular. Spaced from the concavity 12 is a shoulder 15 upon which abuts a block 16 formed preferably of wood, or other suitable penetrable material. It will be seen that the block 16 fits snugly in the central aperture of the plastic body and is curved on its upper surface as at 14 in conformity with the concavity 12.

Disposed between the block 16 and the plastic body 10 is an insert 17 formed preferably of sheet metal or the like, and shown best in Fig. 5. This insert extends into the plastic body as at 18 and has a peripheral ridge 20 formed integrally therewith. Obviously, the ridge 20, which may be in the form of any suitable irregularity, may be in the form of nodules or other irregularities. The function of this ridge is to secure the insert 17 to the plastic body. Furthermore, it will be obvious that this ridge or irregularities may be entirely eliminated, if desired, and the insert merely made to extend into the plastic body, as shown at 18. However, I have shown both means for securing the insert to the plastic body.

The insert 17 has a peripheral flange 22 which is crimped over so as to securely engage the block 16 for retaining it in the central cavity of the plastic body.

Disposed in the central cavity of the plastic body, adjacent the lower portion thereof, is another block 23, similar in composition to the block 16, this block being secured in a cup-shaped member 25 formed preferably of sheet metal and abutting against a shoulder 25' in the plastic body. The cup-shaped member 25, as best seen in Fig. 7, has a peripheral flange 26 which extends around the bottom of the molded body 10 so as to form

a guard theretor, and has a peripheral edge 28 for securing it to the molded body, which ridge may be reversed for securing the block 23 in place. Apertures 29 are formed in the 5 insert 25 through which screws 30 are passed for securing the block 23 to the cup-shaped member. A lift 32 may be secured to the bottom of the heel by means of cement, nails, or other suitable means.

10 It will be obvious, of course, that the block 16 will serve as a base upon which may be tacked the leather portion of the shoe indicated generally at 35 (Fig. 2) and that the flange 26 of the insert 25 will serve to protect 15 the plastic body when a tool is applied to the lower portion of the heel for removing the lift 32.

In the manufacture of the heel such as is described above, the plastic body 10 is formed 20 in a mold of suitable shape and the inserts 17 and 25 are preferably molded into the plastic body 10. It will be readily apparent to those who are familiar with the art that the central cavity 13 is filled with a suitable core, during 25 the molding operation and that this core is removed after the plastic body has hardened. The block 23 is then driven into the insert 25 and secured therein by means of the screws 30 and the block 16 is driven into its 30 insert 17 and the flange 22 of the insert is crimped over so as to secure the block therein. The heel is now ready to have the lift 32 applied thereto either by means of tacks or cement, and may then be applied to the shoe 35 by means of tacks engaging the block 16.

Referring now to the embodiments of Figs. 3 and 6, there is provided a plastic tubular body 40 formed of a phenol condensation product or other suitable plastic material and 40 substantially similar in contour to the heel of the other embodiment. The plastic body 40 has a central cavity 41 with shoulders 42 and 43 formed therein. Disposed in the upper portion of the plastic body in the central 45 cavity 41 thereof, is an annular insert 45, preferably formed of sheet metal or the like and having thereon a peripheral ridge 46 similar to that of the previous embodiment. Also formed integrally with the insert 45 is a plurality of teeth 47, these teeth being preferably struck out from the main body of the insert 45. Disposed within the insert and securely retained therein by means of teeth 47 is a block 48 preferably formed of wood or other 50 penetrable material.

While the insert 45 is shown as secured to the plastic body 40 by means of a peripheral ridge 46, it will be obvious that the insert may be made so as to extend into the plastic body 60 as in the embodiment of Fig. 2, is so desired.

Disposed in the central cavity 41 adjacent the lower end of the plastic body 40 and abutting against the shoulder 43 is a block 50 of penetrable material and interposed between 65 the block 50 and the plastic body is a metal-

lic insert 51. This insert is substantially similar to the insert 45, having struck-out teeth 52 integral therewith and an integral ridge or groove 53 for retaining the insert in the metallic body. A lift or rubber heel 54 may be secured to the plastic heel by means of brads 55 or by cement, if so desired. As shown in Fig. 3, brads 55 are used, these brads penetrating into the block 50. It will be readily apparent that the blocks 50 and 48 are retained in the cavity of the plastic body by means of the struck-out teeth 47 and that the inserts are retained therein by means of the peripheral ridges 46 and 53. The insert 51 has a peripheral flange 56 extending around the lower edge of the plastic body so as to protect the same substantially in the same manner as the flange 26 in the embodiment of Fig. 2.

In the manufacture of the heel shown in Fig. 3, the plastic body is molded in a manner substantially similar to that of the other embodiment, the inserts 45 and 51 being molded into the plastic body. It will be readily understood that the inserts 45 and 51 are preferably first formed with the teeth formed therein but not struck out therefrom to any appreciable extent. Hence the usual core may without difficulty be placed within the central cavity and removed therefrom. After the molding step, the teeth are made to project from the walls of the inserts by inserting a tool thereunder and forcing them out, or by other suitable means.

The embodiment shown in Fig. 4 comprises a plastic body 60 which is substantially similar to the plastic bodies of the other embodiments and having a block 61 and a metallic insert 62 disposed in the upper portion thereof, all substantially similar to the embodiment of Figs. 1 and 2. In this embodiment, however, there is a central cavity 64 which does not extend entirely through the plastic body, this body being closed at its lower end, as shown at 65. A plate 66 preferably of metal, or the like, is secured to the bottom of the plastic body by means of integral struck out portions 67 penetrating the plastic body, or by other suitable means. A lift, or rubber heel, 68, may be secured to the bottom plate 66 by means of cement, screws, or the like.

It will be readily understood that in this device the plastic body is molded substantially as in the other embodiments with the insert 62 and the plate 66 secured thereto in the molding operation. In this embodiment the plate 66 serves to protect the bottom of the plastic body from injury by a tool when an old lift is removed therefrom.

In Fig. 8, I have shown a tubular plastic body 70 similar to that of Figs. 1 and 2, with a penetrable block 72 retained therein by means of a metallic insert 73. This insert is similar to the insert 17, except that it has a peripheral flange 74 coacting with a groove 75

75 in the block 72 for retaining the latter in place.

From the preceding, it will be noted that in all the constructions there is provided an exposed portion of a moisture impermeable material which will stand a great amount of wear and which will always maintain its shape, which has a natural high lustre and may be of any color or finish, or any combination of colors, requires no covering, and is of light weight without having any of the disadvantages of wood or other similar material.

Having thus described my invention, it is obvious that various immaterial modifications may be made in the same without departing from the spirit of my invention; hence I do not wish to be understood as limiting myself to the exact form, construction, arrangement and combination of parts herein shown and described or uses mentioned.

What I claim as new and desire to secure by Letters Patent is:

1. In a device of the class described, a hard molded body formed of plastic material, means molded into said body for protecting an edge thereof from a tool or the like, and a penetrable member secured by said protecting means.
2. In a device of the class described, a molded body formed of plastic material, a plate molded into said body for protecting an edge thereof from a tool or the like, and a penetrable member secured by said plate.
3. In a device of the class described, a hard molded body formed of plastic material and having a cavity therein, a penetrable member secured in said cavity and flush with one surface of said body, and a substantially annular member molded into said molded body for retaining said penetrable member.
4. In a device of the class described, a hard molded body formed of plastic material and having a cavity therein, a penetrable member secured in said cavity and flush with one surface of said body, and a substantially annular member molded into said molded body for retaining said penetrable member, said substantially annular member having a deformation thereon engaging said molded body to form a secure connection therewith.
5. In a device of the class described, a hard molded body formed of plastic material and having a cavity therein, a penetrable member secured in said cavity and flush with one surface of said body, a member molded into said molded body for receiving said penetrable member, and means on said member for securing said penetrable member therein.
6. In a device of the class described, a hard molded body formed of plastic material having a cavity therein, a penetrable member secured in said cavity and flush with one surface of said body, means molded into said

molded body for receiving said penetrable member, and a flange on said last named means crimped over said penetrable member for securing the same in place.

7. In a device of the class described, a hard molded body formed of plastic material and having a cavity therein, a penetrable member secured in said cavity and flush with one surface of said body, a metallic member molded into said molded body for receiving said penetrable member, and means struck out from said metallic member and engaging said penetrable member for retaining the same in place.

8. In a device of the class described, a hard molded body formed of plastic material, a member formed of sheet metal or the like and molded into said molded body, said member having a deformation thereon for rigidly securing it to said molded body, and means struck out from said member for engaging an insert of penetrable material.

In witness whereof, I hereunto subscribe my name this 12th day of November, A. D. 1928.

ISIDORE SIMON.
